(57) **CLAIM**

The ornamental design for a set of medical device accessory bags, as shown and described.

DESCRIPTION

FIG. 1 is a top, front, right-side perspective view of a set of medical device accessory bags;

FIG. 2 is a top, front, left-side perspective view thereof;

FIG. 3 is a top, back, left-side perspective view thereof;

FIG. 4 is a bottom, back, right-side perspective view thereof;

FIG. 5 is a front view thereof;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The dashed broken lines depict portions of the set of medical device accessory bags and environmental context of the set of medical device accessory bags that form no part of the claimed design.

1 Claim, 10 Drawing Sheets
